UNITED STATES PATENT OFFICE.

ARTHUR LEWIS CARNELL, OF DUNGOG, NEW SOUTH WALES, AUSTRALIA.

PIN-POINT CATCH.

1,144,638.

Specification of Letters Patent. Patented June 29, 1915.

Application filed June 17, 1913. Serial No. 774,155.

To all whom it may concern:

Be it known that I, ARTHUR LEWIS CARNELL, subject of the King of Great Britain and Ireland, residing at Dowling street, 5 Dungog, in the State of New South Wales, Commonwealth of Australia, have invented new and useful Improvements in Pin-Point Catches, of which the following is a specification.

- 10 The essential feature of the invention consists in pivoting the catch so that it can oscillate, when required, from side to side. The pivot is, preferably, placed on one side of the catch, so that the catch can oscillate 15 in a horizontal plane. Upon the pivot pin is articulated the catch which consists of a small cylinder or an oval with a zig-zag curved slot on the side opposite the pivot. The pin will be introduced into the catch 20 by turning the latter slightly to one side when the pin will be introduced into one end of the curved slot and pushed home; the catch will automatically straighten itself and be parallel with the longitudinal axis 25 of the brooch or safety pin. When the brooch or safety pin is to be removed, the catch will be turned on its pivot when the point of the pin will slip out of the curved slot in the catch.
- 30 In the accompanying drawings;—Figure 1 is a side elevation of the pin and catch fastening. Fig. 2 is a side elevation of the appliance the catch having been turned to admit the pointed end of the pin into the slot. Fig. 3 is a plan of the same. Fig. 4 is a perspective view of the appliance. Figs. 5, 6 and 7 are, respectively, a plan, front elevation and end elevation of the catch, drawn to a slightly larger scale.
- 40 A is the base, which may represent either the front of a brooch or the rigid bar of a safety pin; B is the pin secured to the brooch, or the rigid bar of a safety pin, at b, in the usual manner. At a point on one side 45 of the point of the pin B is placed the pivot pin C, and swiveled on the pivot pin C is the catch D. If the catch be made in cylindrical form the pivot pin may pass through the center of the cylinder at right angles to its

longitudinal axis, but I have found that a 50 good form for the catch is a flat oval, as shown in the drawings, in which case the catch will be pivoted at c on the pin C at one side, so that the catch can oscillate to a small extent, in a vertical plane. In the 55 side of the catch D opposite the pivot pin C is a curved slot E of zig-zag form, as is clearly shown in Fig. 6.

When it is desired to fasten the point of the pin in the catch, the latter will be turned 60 at an angle, as shown in Figs. 2 and 3, the point of the pin B will be laid in the end of the slot E, the catch D may then be turned on its pivot so as to lie parallel with the axis of the pin and the point of the pin 65 will lie securely within, and be shielded by, the catch. In order that the back of the catch D shall not foul the pin, the back of the pin is cut out in a curve d, as may be seen on referring to Figs. 1, 2, 4 and 6. If 70 the point b be provided with a spring in torsion (which would always be the case with a safety pin), the pin B will rise and assume the position shown in Figs. 1 and 4, but with a brooch the spring would not be essential 75 as the material that is perforated by the pin would have very much the same effect.

I claim:—

1. In combination, a pin including a back, a pointed member pivoted to the back, and 80 a tubular catch member pivoted to the back adjacent to the free pointed end of the pin upon a vertical axis, the said catch member being adapted to be moved into parallel relation with respect to the pin in securing position, or into angularly arranged releasing position, the said member having a tortuous slot in one of its sides opening through its ends and adapted to admit the pin point only when the member is in releasing position. 90
2. In combination, a pin including a back, a point pivoted to the back, and a tubular catch member pivoted to the back adjacent to the free pointed end of the pin upon a vertical axis, the said catch member being 95 adapted to be moved into parallel relation with respect to the pin in securing position, or into angularly arranged releasing posi-

tion, the said member having a tortuous slot in one of its sides opening through its ends and adapted to admit the pin point only when the member is in releasing position, 5 the opposite side of the catch member being provided terminally and opposite to the said slot with an auxiliary notch.

In testimony whereof I have signed my name to this specification in the presence of two subscribing witnesses.

ARTHUR LEWIS CARNELL.
